UNITED STATES PATENT OFFICE.

JOHN B. GABRIELSON, OF HANOVER, PENNSYLVANIA.

RADIATOR.

1,362,615.

Specification of Letters Patent. Patented Dec. 21, 1920.

Application filed July 18, 1919; Serial No. 311,766.

To all whom it may concern:

Be it known that I, JOHN B. GABRIELSON, a subject of the King of Sweden, residing at Hanover, in the county of York and State of Pennsylvania, have invented certain new and useful Improvements in Radiators, of which the following, taken in connection with the accompanying drawings, is a specification.

10 The invention relates to radiators for motor driven vehicles; and the object of the improvement is to provide a radiator core construction in which provision is made for the absolute holding in alinement of the 15 different corrugated or zigzag plates which form said core in their contacting relation to one another so that when assembled, said plates form zigzag or serpentine waterways which extend around one side of each of 20 the air flues, that is, said waterways are preferably alternated with a spacing plate, said spacing plate being held absolutely in alinement by lengthwise ridges or protuberances on opposite edges of the flat contacting faces so that the spacing plate fits 25 between said ridges and is held rigidly in line when the ends of the assembled plates are dipped in a solder bath, said alining means holding the thin sheet metal plates 30 for the entire length of said waterway; and the invention consists in the novel features and combinations hereinafter set forth and claimed.

In the drawings, Figure 1 is a perspective 35 sectional view of a portion of the sheet metal core, showing the waterways and spacing plates held in alinement; and Fig. 2 is a front elevation of said portion of said core further showing the manner of holding 40 the thin sheet metal plates in alinement. Fig. 3 is a perspective view of one of the plates showing the lengthwise holding ridge on the opposite sides of adjacent corrugations in the zigzag plates forming 45 the waterways. Fig. 4 is a perspective view of one of the spacing plates which does not have said holding ridge, but is fitted between said lengthwise ridges, the width of the flat portions of the zigzag spacing plates being 50 proportioned to the flat surfaces of the corrugated or zigzag plates for the waterways.

Like characters of reference refer to corresponding parts in the several views.

The numeral 10 designates the radiator core which is made the desired size for cool-

ing the water in the motor. The radiator core 10 is made up of zigzag waterways 11 which are formed by zigzag plates 12 and 13 and spacing plates 18. The zigzag plates 12 and 13 have their central portions 60 bent in opposite directions to form the waterway 11 therebetween.

Each of the plates 12 and 13 have the ridge or protuberances 14 lengthwise of the corrugations and on opposite sides of the 65 flat portions 15 and 16 so as to hold the flat portions 17 of the spacing plate 18 therebetween, that is, between the alternate projecting lengthwise ridge bends 14 upon the flat spaces 15 and 16 in the metal plates 12 70 and 13.

The lengthwise ridge bend 14 consists of a continuation of the enlarging bends 19 in the two plates 12 and 13 which form the waterway to form an extending lengthwise 75 protuberance. This continuation of the sidewise bend 19 into a groove on the inner side and lengthwise ridge or protuberance on the outer side does not strain or break the thin sheet metal and forms a peculiarly 80 strong holding means for the central spacing plate 18 between the two projecting ridges 14 on the spaced flat surfaces 15 and 16. The exceedingly thin sheet metal, preferably copper, which forms the plates 12, 13 85 and 17 are easily struck up by a suitable die into the lengthwise ridges 14 at the same time that the entire plate is struck up. It is apparent that when assembled, as shown 90 in Figs. 1 and 2, the contacting ends 20 may be dipped in solder, thereby holding all parts rigid in relation to one another. The alternate projecting ridges 14, however, hold the plates so firmly together that 95 assembling is exceedingly easy and the plates cannot get out of line in the finished radiator core.

The placing of the lengthwise ridges 14 on the opposite sides of the two corrugated metal sheets 12 and 13 are preferably staggered in their relation to one another, that is, the ridges 14 on one side of the two plates when assembled are on opposite sides of one pair of flat surfaces of said corrugated plates, while the ridges 14 on the opposite side of the two assembled plates are staggered in opposing relation so that the plates are held more firmly in line as to one another at every corrugation.

The plates 12 and 13 between the flat sur- 110

faces 15 and 16 are preferably corrugated or undulating in order to give a larger radiating surface as shown in my former Letters Patent No. 1,217,934, dated March 6, 5 1917.

I claim as new:

1. In a radiator core, pairs of corrugated plates spaced to form vertical waterways and formed to have spaced flat vertically 10 arranged walls, a ridge adjacent the upper edge and a corresponding ridge adjacent the lower edge of alternate flat walls of said plates, and corrugated spacing plates having flat walls seated against the first named flat 15 walls and said ridges overlapping and underlapping the respective divergent walls of the spacing plates, said ridges being composed of outwardly extending bends formed at the juncture of the flat walls with the adjacent divergent walls of the first named 20

plates, whereby to positively engage and support each corrugation at three points.

2. In a radiator core, pairs of corrugated plates spaced to form vertical waterways and formed to have spaced flat walls, a 25 ridge borne by each wall and extending outwardly therefrom, and corrugated spacing plates having flat walls seated against the first named flat walls, the ridges lapping and engaging the inner faces of the respective divergent walls of the spacing plates, 30 whereby to positively engage and support each corrugation at three points.

In testimony whereof I have affixed my signature in the presence of two witnesses. 35

JOHN B. GABRIELSON.

Witnesses:

HAROLD FORSBERG,
C. V. SWANSON.
